FURNITURE CONSTRUCTION

Filed April 27, 1928

INVENTOR

E. ROOS

BY *Mann & Co.*

ATTORNEY

UNITED STATES PATENT OFFICE.

EDWARD ROOS, OF FOREST PARK, ILLINOIS.

FURNITURE CONSTRUCTION.

Application filed April 27, 1928. Serial No. 273,311.

My invention relates to improvements in furniture constructions, and it consists in the combinations, constructions, and arrangements herein described and claimed.

- 5 An object of my invention is to provide a means for increasing the general surface of red cedar heartwood which is finally formed into cedar chests, clothes closets, or the like, whereby a greater amount of cedar oil fumes 10 may pass therefrom. It is a well known fact that cedar oil fumes pass from the usual red cedar heartwood. The amount of the oil fumes allowed to pass from the wood depends upon the exposed surface of the wood.
- 15 A further object of my invention is to provide a construction of the type described in which red cedar heartwood may be used as a core for a veneered furniture construction and provided with a sufficient means for allowing a certain amount of oil fumes to pass 20 therefrom.

A further object of my invention is to provide a construction of the type described wherein a chest may be formed and provided 25 with any desired area of exposed cedar surfaces for allowing any desired portion of cedar oil fumes to pass therefrom.

Other objects and advantages will appear in the following specification, and the novel 30 features of the invention will be particularly pointed out in the appended claims.

My invention is illustrated in the accompanying drawings, forming part of this application, in which

35 Figure 1 is a longitudinal sectional view of a chest illustrating my invention,

Figure 2 is a lateral sectional view of a chest illustrating my invention,

40 Figure 3 is an enlarged detail of a portion of the chest, and

Figures 4 and 5 are plan views of cedar boards embodying my invention.

In carrying out my invention, I show as a means of illustration a chest 1 composed of 45 a front wall 3, a back wall 2, end walls 4 and 5, a bottom 6, and a top 7. The front wall 2, the end walls 3 and 4, and the top 7 are provided with a veneered construction, as will be explained, and the bottom 6 and the rear 50 wall 3 are provided with solid cedar boards.

The veneered construction, which is embodied in the top, front, and end walls, may be of three, five, seven ply or of as many plies as desired. In the present instance I 55 have shown a five ply construction which con-

sists of a core 8 of cedar wood, preferably of red cedar heartwood. Layers of cross banding 9 and 10 are placed adjacent and secured to the core 8. The outer layer 11 and inner layer 12 are then disposed upon the cross banding. The inner layer 12 is of red cedar. The cross banding and the outer layer may be constructed of any desired material or wood, such as walnut. In this manner veneered constructions of any desired design 60 may be formed.

A novel means is provided for allowing the escapement of the oil fumes from the core 8 of each of the veneered portions. This constitutes the provision of a multiplicity of 70 elongated recesses or slots 13 which extend through the inner layer 12, the cross banding 10, and a sufficient distance into the heart of the core 8. This formation permits an escapement of the fumes from the core and provides an exposed surface greater than the area of one side of the core. In this manner more than the ordinary result may be obtained from the core by the provision of the slots 13. It will be noted that the slots 13 are 80 disposed relatively close together and in parallel arrangement.

The bottom 6 and the back 2 are provided with a multiplicity of elongated slots 14 which are similar in formation to the slots 85 13. With this construction the intrinsic value of the wood may be increased to a maximum.

As stated heretofore, the amount of cedar oil fumes passing from the cedar wood depends upon the exposed area of the cedar wood, together with the thickness of the wood. In veneered construction it is necessary to place the equal number of layers upon the inside portion as is applied upon the outside 90 portion. Therefore, a chest formed of veneered construction cannot produce the sufficient supply of oil fumes with merely a back and a bottom portion of plain cedar and thin plies of cedar such as that indicated at 100 12 upon the veneered portions. Therefore, the provision of the multiplicity of grooves or slots 13 provides a communication between the interior of the chest and the core 8 of each of the veneered portions and provides 105 an area of exposed surfaces sufficiently large to produce the proper amount of cedar oil fumes.

In Figure 4 I have shown a cedar board 15 which is provided with a multiplicity of elong-

gated grooves or slots 16 which extend inwardly substantially half the width of the board. In Figure 5 I have shown a cedar board 17 which is provided with a multiplicity of openings 18 which are drilled into the board approximately half the width thereof. The slots 16 or the openings 18 provide a means for increasing the surface area of one side of the boards. These boards 10 may be used for forming any structure, such as linings for closets, trunks, chests, or the like.

I claim:

- 15 1. A construction of the type described comprising a veneered portion, a core for said veneered portion, and means for providing exposed portions of said core.
- 20 2. A construction of the type described comprising a core, veneering disposed upon said core, and means for exposing an area of surface of said core.

3. A construction of the type described comprising a body portion formed of wall portions, one or more of said wall portions being formed of veneered construction having a central core, and means for exposing to the interior of said body portion a surface area of said core. 25

4. A construction of the type described including a veneered portion comprising a core formed of cedar wood, layers of veneering disposed upon opposite surfaces of said core, and means for exposing a relatively large amount of surface area of said core, said means comprising a plurality of slots extending through the veneering upon one side of said core and into said core. 30

Signed at Forest Park in the county of Cook and State of Illinois, this 24th day of April, A. D. one thousand nine hundred 40 twenty-eight.

EDWARD ROOS.
